Primary Examiner—A. Hugo Word*Assistant Examiner*—Holly Baynham*Attorney, Agent, or Firm*—Jacox, Meckstroth & Jenkins[57] **CLAIM**

The ornamental design of an adjustable safety rail support bracket for a roof surface, as shown and described.

DESCRIPTION

FIG. 1 is a perspective view of an adjustable safety rail support bracket for a roof surface showing my new design; FIG. 2 is a side view thereof, the opposite side view being shown in FIG. 1;

FIG. 3 is an end view thereof;

FIG. 4 is an opposite end view thereof;

FIG. 5 is a top view thereof;

FIG. 6 is a bottom view thereof;

FIG. 7 is a perspective view of another embodiment thereof;

FIG. 8 is a side view of the other embodiment, the opposite side view being shown in FIG. 7;

FIG. 9 is an end view of the other embodiment;

FIG. 10 is an opposite end view of the other embodiment;

FIG. 11 is a top view of the other embodiment; and,

FIG. 12 is a bottom view of the other embodiment.

The broken line showing of fragmented structure is for illustrative purposes only and forms no part of the claimed design.
